TUBULAR ATTACHMENT WICK

Gustav Walters, Middletown, Conn., assignor to
The Russell Manufacturing Company, Middletown, Conn., a corporation of Connecticut

Application August 31, 1938, Serial No. 227,707

4 Claims. (Cl. 67—70)

This invention relates to improvements in tubular wicks, and more particularly to tubular wicks for attachment to main wicks used in oil stoves, and the like.

One object of this invention is to provide an improved tubular attachment-wick adapted to be easily and firmly secured on top of a tubular main wick of a common type used in oil stoves and the like.

Another object of this invention is to provide an improved tubular attachment-wick characterized by long life, to be secured on top of a tubular main wick of a common type used in oil stoves and the like.

Another object of this invention is to provide an improved tubular attachment-wick having simple and efficient attachment-means readily manufactured and readily assembled with the attachment-wick, and with the main wick to which the attachment-wick is to be applied.

With the above and other objects in view as will appear to those skilled in the art from the present disclosure, this invention includes all features in said disclosure which are novel over the prior art.

In the accompanying drawing, in which one way of carrying out the invention is shown for illustrative purposes:

Fig. 1 is a perspective view of a tubular attachment-wick made in accordance with the present invention;

Fig. 2 is a central vertical sectional view through the attachment-wick and the prongs;

Fig. 3 is a front elevation of a main wick and carrier with the attachment-wick mounted thereon;

Fig. 4 is a central vertical sectional view similar to Fig. 2 with the attachment-wick secured in place on the main wick;

Fig. 5 is a front elevation of a punched-out attachment-strip for forming the attachment-means for the tubular attachment-wick;

Fig. 6 is a view similar to Fig. 5 with the attaching elements thereof bent to attaching position;

Fig. 7 is a sectional view on line 7—7 of Fig. 6; and

Fig. 8 is a sectional view similar to Fig. 7, of a modified construction.

In the description and claims, the various parts are identified by specific names for convenience, but they are intended to be as generic in their application as the prior art will permit.

Referring to the drawing, the particular form of the invention herein chosen for illustration in-

cludes a tubular attachment-wick or cap-wick or replacement-wick 10 to which an attachment-member or clip or band 11, preferably formed from thin resilient sheet-metal, which may be a rustless metal if desired, is secured by means of clamping-prongs 12, the extreme ends 13 of which are bent over or clamped to the wick 10 to firmly secure the band or clamping-member 11 to the wick. The attachment-member or band 11 may be made in various ways. In the particular construction illustrated in the drawing, it is first formed as a straight strip of thin resilient sheet-metal having oppositely-projecting prongs 12 and 14. The prongs 12 are bent over at right angles, as shown in Figs. 6 and 7, and the extreme ends of the prongs 14 are bent over to form anchoring-hooks 15. Instead of making the anchoring-hooks 15 at right angles to the body-portion of prongs 14, anchoring-hooks 15a may be employed as shown in Fig. 8, arranged at an acute angle to the body-portion of the prongs. If desired, before applying the band 11 to the wick 10, the band 11 can be formed up into ring form and have the abutting ends 16 joined together by butt-welding or other suitable means. Or, if desired, the attachment-band 11 can be used without joining the ends 16 together, in which case attaching-prongs similar to prongs 12 can be added adjacent the ends 16 to secure the ends of the band 11 to the wick 10. Or, the band 11 with the prongs 12 and 14, can be punched out from a tube, so as to be seamless and free of any joint. The wick 10 may be of any desired construction or material.

One important use for my improved attachment-wick construction is where the main-wick 17 mounted in a carrier 18 has been burned down to be no longer serviceable, such, for example, as being burned down to approximately the top-edge 19 of the carrier 18. In such case, the attachment-wick construction illustrated in Fig. 1 can be grasped in the hand and moved downward to cause the prongs 14 to be inserted between the top-edge portion of the main wick 17 and the wall of the carrier 18, to the position illustrated in Figs. 3 and 4, and while the abutting edges 20 of the wicks 10 and 17 are held in firmly-pressed-together relation, the operator's fingers are pressed against the inner surface 21 of main-wick 17 to force the wick over the hooks 15 (or 15a) to firmly anchor the hooks in the wick 17. As thus assembled, oil is carried by capillary action from main-wick 17 across the abutting wick-edges 20 to wick 10 and is burned at the top of the wick 10. It will be obvious that by detaching

the hooks 15 (or 15a) from the main-wick 17, the wick 10 can be removed or detached from its place on top of main-wick 17. An attachment-wick employing a wick-member made, for example, in accordance with the disclosure of either of my applications for patent entitled "Woven wick," Serial No. 227,705, or "Tubular felted wick," Serial No. 227,708, both filed August 31, 1938, provides a wick having long life.

10 The invention may be carried out in other specific ways than those herein set forth without departing from the spirit and essential characteristics of the invention, and the present embodiments are, therefore, to be considered in all 15 respects as illustrative and not restrictive, and all changes coming within the meaning and equivalency range of the appended claims are intended to be embraced therein.

I claim:

20 1. In combination: a tubular main wick mounted in a tubular wick-carrier; a tubular attachment-wick mounted in end-abutting relation on said main wick; a tubular band secured to, and having its upper edge lower than the 25 upper edge of, and its lower edge not lower than the lower edge of, said attachment-wick; prongs carried by and projecting from said tubular band longitudinally of said wicks down past the abutting ends of said attachment-wick and said main 30 wick and having hooks at their lower ends engaging said main wick.

2. In combination: a tubular main wick mounted in a tubular wick-carrier; a tubular attachment-wick mounted in end-abutting relation on said main wick; a tubular band surrounding and secured to, and having its upper edge

lower than the upper edge of, and its lower edge not lower than the lower edge of, said attachment-wick; prongs carried by and projecting from said tubular band longitudinally of said wicks down past the abutting ends of said attachment-wick and said main wick and between said carrier and said main wick and having inwardly-directed hooks at their lower ends engaging said main wick.

3. A tubular attachment-wick unit comprising: 10 a tubular attachment-wick; a tubular band secured to, and having its upper edge lower than the upper edge of, and its lower edge not lower than the lower edge of, said attachment-wick; prongs carried by and projecting from said tubular band longitudinally of and down past the lower edge of said attachment-wick and having hooks at their lower ends for engagement with a tubular main wick; said attachment-wick unit 15 constituting an article of manufacture designed and adapted to be attached as a unit to a tubular main wick.

4. A tubular attachment-wick unit comprising: 20 a tubular attachment-wick; a tubular band surrounding and secured to, and having its upper edge lower than the upper edge of, and its lower edge not lower than the lower edge of, said attachment-wick; prongs carried by and projecting from said tubular band longitudinally of and down past the lower edge of said attachment-wick and having inwardly-directed hooks at their lower ends for engagement with a tubular main wick; said attachment-wick unit 25 constituting an article of manufacture designed and adapted to be attached as a unit to a tubular main wick.

GUSTAV WALTERS.
